UNITED STATES PATENT OFFICE.

THOMAS ADAMS, OF HIGHLAND, NEW YORK.

DESIGN FOR A FOLDING CHAIR.

SPECIFICATION forming part of Design No. 31,698, dated October 17, 1899.

Application filed September 23, 1899. Serial No. 731,494. Term of patent 14 years.

To all whom it may concern:

Be it known that I, THOMAS ADAMS, a citizen of the United States, residing at Highland, in the county of Ulster and State of New York, 5 have invented and produced a new and original Design for Folding Chairs, of which the following is a specification.

My invention relates to a new and original design for a folding chair; and the essential o feature consists in the ornamental configuration given to the frame thereof.

In the accompanying drawing the figure represents a perspective view of a folding chair constructed according to my design.

5 In the said drawing the reference-numeral 1 designates two side bars, forming combined arms and legs. The upper ends of these bars are curved backwardly, forming arms 2, with their upper ends formed with rounded knobs o 3, and are connected together by a transverse ornamental bar 4. The lower ends of said arms are also formed with ornamental knobs 5.

The numeral 6 designates the curved connected legs formed by the lower ends of the

bars and the lower ends formed with curved 25 knobs 7. The said arms and legs are connected by curved ornamental intermediate portions 8.

The numeral 9 designates horizontal side bars connected together at front and rear 30 and provided at the rear ends with curved knobs 10, forming ornamental feet.

The numeral 12 designates the seat, and 13 a support for the arms, consisting of a transverse arm provided with an upwardly - ex- 35 tending arm at each end. The horizontal arm engages with notches in the side bars 9.

What I claim is—

The design for a folding chair, substantially as herein shown and described. 40

In testimony whereof I have hereunto set my hand in presence of two subscribing witnesses.

THOMAS ADAMS.
